Haven, Conn., a corporation of Maryland

Application December 19, 1933, Serial No. 703,035

18 Claims. (Cl. 42—69)

This invention relates to an improvement in firearms and has for one of its objects the provision of superior means for guarding against the accidental discharge of the arm.

Another object of the present invention is to provide a simple, reliable and effective firearm construction wherein the movement of the trigger itself automatically effects the locking of the sear when rearward draft is released from the trigger.

Another object is to provide a mechanism suitable for the class of firearms commonly known as "semi-automatic", which will effectively guard against the unintentional firing of a second shot after the arm has been automatically reloaded.

A still further object is to provide superior means whereby the release of the firing-pin or other firing member of the arm is automatically guarded against when the breech-bolt is in other than its fully-closed position.

Other objects and advantages will appear to those skilled in the art from the following, considered in conjunction with the accompanying drawings and the appended claims.

In the accompanying drawings:

Fig. 1 is a broken view in side elevation of one form which a firearm embodying the present invention may assume, with a portion of the frame-cover broken away;

Fig. 2 is a similar view on an enlarged scale but with certain of the parts shown in vertical central section and the firearm being shown as cocked preparatory to firing;

Fig. 3 is a view corresponding to Fig. 2 but showing the effect of the initial sear-unlocking movement of the trigger;

Fig. 4 is a similar but less comprehensive view, showing the positions which the parts assume at the instant the arm is fired;

Fig. 5 is a view similar to Fig. 3 but showing the positions which the parts assume when the trigger is fully pulled and the arm fired;

Fig. 6 is a transverse sectional view taken on the line 6—6 of Fig. 2;

Fig. 7 is a similar view taken on the line 7—7 of Fig. 2;

Fig. 8 is a perspective view of the trigger detached;

Fig. 9 is a perspective view of the sear detached;

Fig. 10 is a similar view of the transmitting-member detached;

Fig. 11 is a view partly in side elevation and partly in vertical section corresponding to Fig. 2

but showing another form which the present invention may assume;

Fig. 12 is a perspective view of the sear of the firearm shown in Fig. 11;

Fig. 13 is a view partly in side elevation and partly in vertical longitudinal section of still another form which a firearm may assume in accordance with the present invention, the arm being shown as cocked;

Fig. 14 is a similar view showing the positions which the parts assume after the gun has been fired and after the breech-bolt has started its rearward travel;

Fig. 15 is a similar view but showing the positions which the parts assume after the gun has been fully cocked, the bolt has been returned to its fully-closed position—the trigger still being held in its rearward position;

Fig. 16 is a top or plan view of the frame-partition of the firearm and the portion of the butt-stock upon which the same is mounted, the pivotal hammer being shown partly in horizontal section;

Fig. 17 is a transverse sectional view taken on the line 17—17 of Fig. 13;

Fig. 18 is a perspective view of the trigger of the firearm of Figs. 12 et seq.;

Fig. 19 is a similar view of the sear detached; and

Fig. 20 is a similar view of the transmitting-member detached.

The embodiment of the present invention herein chosen for illustration in Figs. 1 to 10 inclusive includes a frame 20 having a mechanism-receiving chamber 21 therein which opens laterally on one side, as clearly indicated in Figs. 5 and 6. The said frame is provided with a usual trigger-guard 22 and is secured to the forward end of a butt-stock 23.

Fitting over the frame 20 above referred to is 40 a frame-cover 24 of inverted U-shaped form in cross-section and having attached to its forward end the usual barrel 25 and forestock 26.

Reciprocating within the mechanism-receiving chamber 21 of the frame 20 is a breech-bolt 27 45 through the upper portion of which extends a firing-pin 28 provided with the usual firing-point 29 and urged forwardly by a spring 30 located in a spring-receiving bore 31 in the said firing-pin 28. The said spring 30 encircles the reduced forward end of a guide-rod 32 and bears against an abutment-shoulder 33 formed thereon. The rear end of the said guide-rod 32 is seated, as shown, in a shallow socket 34 in the rear wall of the mechanism-receiving chamber 21 of the frame 20. 55

In its under face the firing-pin 28 is formed with a sear-notch 35, the rear wall of which is engaged in the usual manner by a sear-nose 36 forming a feature of a sear 37 mounted within the chamber 21 of the frame 20 upon a pin 38 extending transversely across the said chamber. The said sear is urged in the direction required for engaging its sear-nose 36 with the sear-notch 35 by means of a sear-spring 37a.

At a point forwardly of the pin 38 the sear 37 above referred to is provided with a forwardly-and-upwardly-sloping spring-pocket 39 receiving the lower end of a helical spring 40 having its opposite end seated in a downwardly-and-rearwardly-sloping shallow pocket 41 formed in the under face of a lug 42 laterally offsetting from a plate-like member 43 which for convenience of description may be designated as a "transmitting-member." The said spring 40 exerts a constant effort to move the said transmitting-member forwardly and to rock the same about the pin 38.

The transmitting-member 43 just above referred to is provided with a forwardly-and-upwardly-inclined guide-slot 44 through which extends the pin 38 mounting the sear 37 as previously described.

The forward upper end of the transmitting-member 43 is rounded, as shown, to provide a cam-surface 45 adapted to be engaged on occasion by a rearwardly-and-upwardly-inclined transmitting-member actuating-surface 46 formed in the rear end of the breech-bolt 27 before referred to. The cam-surface 45 is also engaged, for being held in its depressed position by a longitudinal holding-surface 46a formed on the under side of the said breech-bolt and intersecting at the rear end, the actuating-surface 46. The rear shank-like portion 47 of the said transmitting-member 43 extends beneath a guide-lug 48 offsetting from the sear 37 and terminates in what may be suitably termed a transmitting-head 49. The under surface of the transmitting-head 49 normally rests upon a thrust-receiving abutment 50 constituting the upper surface of a lug 51 laterally offsetting from the sear 37 adjacent the guide-lug 48 previously referred to.

The transmitting-head 49 of the transmitting-member 43 also has its forward face 52 upwardly-and-rearwardly-sloped, as shown, for cam-like coaction with a retaining-abutment 53 formed upon a trigger 54 having a usual finger-piece 55 and mounted for rocking movement upon a pin 56 extending transversely through the frame 20. The said trigger 54 is urged in a direction required to move its finger-piece 55 forwardly by a trigger-spring 57, the forward end of which is seated against the bottom of a spring-pocket 58 formed in the rear edge of the said trigger 54.

The retaining-abutment 53 previously referred to of the trigger 54 is intersected by a sear-actuating abutment 59 extending at a substantial right angle with respect thereto and normally overlying the upper edge of the transmitting-head 49 of the transmitting-member 43.

The trigger 54 is also provided with a forwardly-and-upwardly-sloping sear-locking finger 60, the outer end of which constitutes a sear-locking abutment 61 coacting on occasion with a locking-abutment 62 formed by the lower rear corner of the overhanging portion of the sear-nose 36 of the sear 37.

For the purpose of insuring the movement of the sear-locking abutment 61 of the trigger 54

out of the path of the locking-abutment 62 of the sear 37, when the breech-bolt 27 moves rearwardly for cocking the arm, the lower rear corner of the said breech-bolt is provided with a trigger-depressing cam-surface 62a engageable with a rearwardly-and-upwardly-sloping cam-surface 62b formed on the forward end of the trigger 54.

In the event that the trigger 54 is not, at the time, held in its depressed position by the user 10 of the arm, when the breech-bolt 27 is moved rearwardly, the cam surface 62a thereof will engage the cam-surface 62b of the trigger 54 and depress the latter for the purpose above referred to. 15

Let it be presumed that the parts of the firearm are in the positions in which they are shown in Figs. 1 and 2 and that a cartridge is in place in the cartridge-chamber of the barrel 25. It will be seen by reference to the figures 20 referred to that the sear-locking abutment 61 of the trigger 54 is interposed in the path of the locking-abutment 62 of the sear 37, so that the sear-nose 36 cannot be withdrawn from the sear-notch 35 of the firing-pin 28. Thus, the firearm is guarded against accidental discharge until such time as the trigger is intentionally operated, as will be presently described.

Let it now be assumed that it is desired to release the firing-pin 28 for firing the arm. For 30 this purpose, rearward manual pressure will be exerted upon the finger-piece 55 of the trigger 54, with the effect of first swinging the sear-locking abutment 61 of the trigger 54 downwardly and forwardly out of the path of the 35 locking-abutment 62 of the sear 37, as shown in Fig. 3 of the drawings. During the swinging movement of the trigger for the purpose just referred to, the sear-actuating abutment 59 of the said trigger will move toward the upper face 40 of the transmitting-head 49 of the transmitting-member 43, but will not engage therewith, owing to the lost motion provided for, until such time as the sear-locking abutment 61 is swung clear—or substantially clear—of the path of the 45 locking-abutment 62 of the sear 37, also as indicated in Fig. 3.

A continued rearward draft upon the finger-piece 55 of the trigger 54 will cause the sear-actuating abutment 59 of the trigger 54 to exert 50 a downward thrust upon the transmitting-head 49 of the member 43, which thrust will be transmitted thereby to the upwardly-facing thrust-receiving abutment 58 of the sear 37, upon which the under face of the said transmitting-head 55 49 normally rests. This movement will effect the swinging of both the transmitting-member 43 and the sear 37 about the pin 38 as a center, with the effect of ultimately disengaging the sear-nose 36 of the said sear from the sear-notch 35 of the firing-pin 28, whereupon the said firing-pin will be released for rapid forward travel under the urge of its spring 40 to effect the firing of the cartridge in the cartridge-chamber of the barrel 25. Fig. 4 represents the positions 65 which the parts assume at the instant of firing.

The firearm having been discharged, the next normal step in the operation of the same would be the retraction of the breech-bolt 27, which retraction may be effected automatically, as in 70 some types of automatic and semi-automatic firearms, of the character shown in Figs. 1 to 10 inclusive, or manually, as for instance in the so-called "slide-action" type of firearm.

The initial rearward movement of the breech- 75

bolt 27 causes the inclined actuating-surface 46 thereof to engage the cam-surface 45 at the upper forward end of the transmitting-member 43, with the effect, as the bolt continues its rearward movement, of imparting a combined rocking movement and rearward bodily movement to the said transmitting-member 43 against the tension of the spring 40.

The movement of the transmitting-member 43 as just above described serves to shift the transmitting-head 49 thereof rearwardly out of line with the sear-actuating abutment 59 of the trigger 54, thereby permitting the sear 37 to swing upwardly under the urge of the sear-spring 37^a so as to locate its sear-nose 36 in position for reengagement with the sear-notch 35 of the firing-pin 28. The downwardly-facing holding-surface 46^a of the breech-bolt 27 now serves to hold the transmitting-member 43 in the position described until such time as said breech-bolt has been substantially restored to its fully closed position as indicated in Figs. 1 and 2.

The upward swinging movement of the sear 37 as just described carries with it the rear end 5 of the transmitting-member 43, which at this time is resting upon the thrust-receiving abutment 50 of the said sear, and thus shifts the upwardly-and-rearwardly-sloping forward face 52 of the transmitting-head 49 into position for engagement with the retaining-abutment 53 of the trigger 54. The parts will now have assumed the positions in which they are shown in Fig. 5.

In the event that, during the rearward travel of the breech-bolt 27 as above described, the trigger 54 is not at the time held in its depressed position by the user of the arm, the cam-surface 62^a of the breech-bolt 27 will engage with the cam-surface 62^b of the trigger 54 and effect the depression of the latter. Thereafter, until the breech-bolt 27 has been restored substantially to its forward position, the under surface of the said breech-bolt will retain the said trigger in its depressed position, to thus insure the continued displacement of the locking-abutment 61 of the said trigger out of the path of the locking-abutment 62 of the sear 37.

After the breech-bolt 27 has completed its rearward travel and has again been moved forwardly into its substantially-fully-closed position, the downwardly-facing holding-surface 46^a and the actuating-surface 46 of the said breech-bolt will have moved clear of the cam-surface 45 of the transmitting-member 43. The trigger-depressing cam-surface 62^a will at the same time have been moved forwardly entirely clear of the cam-surface 62^b of the trigger 54 to thus permit the said trigger to swing forwardly under the urge of the trigger-spring 57 as soon as the user of the arm has released manual rearward draft thereon.

Upon the forward movement of the breech-bolt as described and the consequent release of the transmitting-member 43, the latter, under the urge of its spring 40, will move forwardly and engage the upwardly-and-rearwardly-sloping forward face 52 of the transmitting-head 49 with the retaining-abutment 53 of the trigger 54 until such time as rearward pressure upon the finger-piece 55 of the said trigger 54 has been released, whereupon the trigger-spring 57 will swing the said trigger and move the retaining-abutment 53 upwardly to a sufficient degree to permit the said transmitting-head 49 to slip under the abutment 59 and complete its forward

movement so as to be restored to the position in which it is shown in Figs. 1 and 2.

The release of rearward pressure upon the finger-piece 55 of the trigger 54 and the consequent swinging movement of the said trigger under the urge of its spring 57, as just described, will again restore the sear-locking abutment 61 to its normal position in which it lies in the path of movement of the locking-abutment 62, of the sear 37 to thus again guard against the accidental release of the firing-pin 28 until such time as the trigger has been intentionally operated.

In the firearm shown in Figs. 11 and 12, no so-called "transmitting-member" is employed to transmit the movement of the trigger to the sear, but a direct actuation of the latter by the said trigger is provided for, as will be presently described.

In the construction shown in the figures referred to, a pivotal sear 63 is employed which 20 is provided with a sear-nose 64 engageable with a sear-notch 65 formed in the under face of a firing-pin 66 corresponding substantially to the firing-pin 28 before described. The said sear 63 is also provided with a locking-abutment 67 engageable on occasion by a sear-locking abutment 68 constituting the upper outer face of a sear-locking finger 69 upwardly-and-forwardly-extending from a trigger 70 pivotally mounted upon a pin 71 and having an integral finger-piece 72 30 urged forwardly by a trigger-spring 73.

The trigger 70 is also provided with a downwardly-facing sear-actuating abutment 74 overlying a thrust-receiving finger 75 forming a rearward extension of the sear 63 before referred to. 35 The said sear 63 is urged in a direction required to enter its sear-nose 64 into the sear-notch 65 of the firing-pin 66 by a helical spring 76, the upper end of which is seated in a spring-pocket 77 opening out of the lower edge of the said 40 sear.

When the finger-piece 72 of the trigger 70 is drawn rearwardly, the sear-locking abutment 68 thereof will be swung forwardly and downwardly clear of the locking-abutment 67 of the sear 63. When in the operation of the trigger the said sear-locking abutment 68 has been moved clear—or substantially clear—of the locking-abutment 67, the sear-actuating abutment 74 of the said trigger will engage with the upper 50 face of the finger 75 of the said sear and by a further movement of the trigger 70, the sear 63 will be swung to disengage its sear-nose 64 from the sear-notch 65 of the firing-pin 66 to release the latter and effect the firing of the arm. 55

When the firing-pin 66 is retired rearwardly, preparatory to being cocked the instant the rear wall of the sear-notch 65 thereof rides clear of the rear end of the sear-nose 64 of the sear 63, the spring 76 will act to reenter the said sear-nose 64 into the sear-notch 65, provided, of course, that the rearward draft upon the finger-piece 72 has been previously released. Thus, as in the construction of Figs. 1 to 10 inclusive, the trigger itself is provided with means for definitely locking the sear against accidental release by jarring or otherwise. In this construction also the reciprocating breech-bolt 71^a is provided with a trigger-depressing cam-surface 71^b co-acting with a cam-surface 71^c on the forward end 70 of the trigger 70 in the same manner as that described in connection with the firearm of Figs. 1 to 10 inclusive.

In the construction shown in Figs. 13 to 20 inclusive, a hammer 78 is pivoted upon a trans-

verse pin 79 and acts to strike the rear end of a firing-pin 80 mounted in a reciprocating breech-bolt 80*. The striking action of the hammer 78 is effected under the urge of a hammer-spring 81 which encircles a guide-rod 82 pivotally coupled at its rear end by means of a pin 83 to the hammer 78 and provided with a forwardly-facing spring-abutment 84 against which the rear end of the hammer-spring 81 presses. The forward end of the hammer-spring 81 is seated against the rear face of the transverse web 85, which latter is provided with a passage 86 in which the forward end of the guide-rod 82 rides.

The hammer 78 is also provided with a sear-notch 87 receiving a sear-nose 88 forwardly-extending from a sear 89 pivotally mounted upon a transverse pin 90. The said sear 89 is urged in a direction required to engage its sear-nose 88 with the sear-notch 87 by a spring 91 housed mainly within a spring-pocket 92 formed in a trigger 93 pivotally mounted upon the pin 90 before referred to.

The trigger 93 is formed in its upper and forward edges with a longitudinal channel 94 receiving, with freedom for relative rocking movement, the sear 89 before referred to. The said trigger 93 also includes a usual finger-piece 95, which latter is urged forwardly by a U-shaped trigger-spring 96, as clearly shown in Figs. 13 and 14.

For effecting the operation of the sear 89 by means of the trigger 93, the said trigger is provided with an upwardly-facing sear-actuating abutment 97 normally overlain by a transmitting-finger 98 laterally offsetting from a sheet-metal transmitting-member 99. The said transmitting-member 99 is provided at its forward end with a laterally-offsetting guide-flange 100 loosely fitting in a forwardly-and-upwardly-sloping transverse guide-notch 101 formed in the frame 102 of the firearm.

The transmitting-member 99 is also formed with a tongue 103 extending into a spring-pocket 104 formed in the frame 102 and engaging the outer end of a spring 105, which latter exerts a constant effort to concurrently move the transmitting-member 99 bodily forwardly and the forward portion thereof upwardly.

The transmitting-finger 98 of the member 99 normally overlies the abutment 97 of the trigger 93 and is itself normally overlain by a thrust-receiving abutment 106 forming the under face of an arm 107 rearwardly extending from the sear 89.

The under face of the breech-bolt 80* constitutes a holding-surface 108 for holding the transmitting-member 99 in its inoperative position, as will be hereinafter described. Sloping rearwardly and upwardly from the holding-surface 108 of the said breech-bolt is a cam-like actuating-surface 109.

When the breech-bolt is in its fully-closed position and the arm is cocked as indicated in Fig. 13, the transmitting-finger 98 of the transmitting-member 99 is interposed between the upwardly-facing sear-actuating abutment 97 of the trigger 93 and the downwardly-facing thrust-receiving abutment 106 of the sear 89 and is yieldingly maintained in such position by the tension of the spring 105. As thus positioned, the transmitting-finger 98 serves to transmit the movement of the trigger 93 to the sear 89 for disengaging the sear-nose 88 from the sear-notch 87 to thus release the hammer 78 and effect the firing of the arm.

After the arm has been fired, should the breech-bolt 80* be moved rearwardly for re-loading and

re-cocking, the sloping actuating-surface 109 of the said breech-bolt will engage the forward end of the transmitting-member 99 and shift the same rearwardly to withdraw the transmitting-finger 98 thereof out from under the thrust-receiving abutment 106 of the sear 89. The movement just described frees the sear 89 from the control of the trigger 93 and permits the spring 91 to reengage the sear-nose 88 with the sear-notch 87 of the hammer 78 when the latter has been swung into its fully-retired position as a result of the rearward travel of the breech-bolt.

After the disengagement of the finger 98 has been effected as above described, the holding-surface 108 of the breech-bolt 80* serves to hold the said finger in such disengaged position until the said breech-bolt is again restored to its forward and substantially-fully-closed position, at which time both of the surfaces 108 and 109 thereof will ride clear of the forward end of the transmitting-member 99.

The clearing of the forward end of the transmitting-member 99 by the complementary surfaces of the breech-bolt 80* as above described will permit the spring 105 to move the said transmitting-member 99 forwardly, and in the event that the rearward draft upon the trigger 93 has not as yet been released, the forward edge of the transmitting-finger 98 will engage with the rear surface of the arm 107 of the sear 89, and will thus be prevented in effect from re-coupling the trigger and sear. Upon the release of the trigger 93, the spring 105 will be free to act to interpose the transmitting-finger 98 of the member 99 between the respective abutments 97 and 106, preparatory to another cycle of operation of the firearm.

As thus constructed, the trigger 93 and sear 89 are in effect uncoupled from each other when the breech-bolt 80* is in any other than its closed, or substantially-closed, position, thus guarding against the accidental firing of a second shot.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. In a firearm, the combination with a trigger; of a sear movable independently of the said trigger; and sear-locking means movable into its unlocking position by the said trigger itself and acting to prevent the accidental releasing-movement of the said sear when the said trigger is in its normal position.

2. In a firearm, the combination with a trigger; of a sear movable independently of the said trigger; and sear-locking means carried by and movable into its unlocking position by the said trigger itself and acting to prevent the accidental releasing-movement of the said sear when the said trigger is in its normal position.

3. In a firearm, the combination with the breech-bolt, trigger and sear thereof; of sear-locking means movable by the said trigger and acting to prevent the accidental releasing-movement of the said sear when the said trigger is in its normal position; and means movable by the said breech-bolt and acting to retire the said sear-locking means.

4. In a firearm, the combination with the

5. In a firearm, the combination with the breech-bolt, trigger and sear thereof; of sear-locking means carried by and movable with the said trigger and acting to prevent the accidental releasing-movement of the said sear when the said trigger is in its normal position; and means movable by the said breech-bolt and acting to retire the said sear-locking means. 5
10. In a firearm, the combination with the breech-bolt, trigger and sear thereof; of sear-locking means movable by the said trigger and acting to prevent the accidental releasing-movement of the said sear when the said trigger is in its normal position; and means carried by and movable with the said breech-bolt and acting to 15 retire the said sear-locking means. 10
15. In a firearm, the combination with the breech-bolt, trigger and sear thereof; of sear-locking means carried by and movable with the said trigger and acting to prevent the accidental releasing-movement of the said sear when the said trigger is in its normal position; and means carried by the said breech-bolt and acting to retire the said sear-locking means. 15
20. In a firearm, the combination with the breech-bolt, trigger and sear thereof; of sear-locking means carried by and movable with the said trigger and acting to prevent the accidental releasing-movement of the said sear when the said trigger is in its normal position; and means carried by the said breech-bolt and acting to retire the said sear-locking means. 20
25. In a firearm, the combination with a trigger; of a sear movable independently of the said trigger; a first locking-abutment carried by the said sear and movable therewith; and a second locking-abutment movable by the said trigger into the path of movement of the said first locking-abutment to guard against the unintentional release of the said sear when the said trigger is in its 30 normal position. 25
30. In a firearm, the combination with a trigger; of a sear movable independently of the said trigger; a first locking-abutment carried by the said sear and movable therewith; and a second locking-abutment carried by and movable with the said trigger into the path of movement of the said first locking-abutment to guard against the unintentional release of the said sear when the said trigger is in its 35 normal position. 30
35. In a firearm, the combination with a trigger; of a sear movable independently of the said trigger; a first locking-abutment carried by the said sear and movable therewith; and a second locking-abutment carried by and movable with the said trigger into the path of movement of the said first locking-abutment to guard against the unintentional release of the said sear when the said trigger is in its 40 normal position. 35
40. In a firearm, the combination with the trigger and sear thereof; of a first locking-abutment carried by the said sear and movable therewith; and a second locking-abutment carried by the said trigger and movable thereby into the path of movement of the said first locking-abutment to guard against the unintentional release of the said sear when the said trigger is in its normal position; one of the said locking-abutments offsetting laterally from the member by which it is carried. 45
45. In a firearm, the combination with the trigger and sear thereof; of a first locking-abutment carried by and movable with the said sear and laterally offsetting therefrom; and a second locking-abutment movable by the said trigger itself into the path of movement of the said first locking-abutment to guard against the unintentional release of the said sear when the said trigger is in its normal position. 50
50. In a firearm, the combination with the trigger and sear thereof; of a first locking-abutment carried by and movable with the said sear and laterally offsetting therefrom; and a second locking-abutment movable by the said trigger itself into the path of movement of the said first locking-abutment to guard against the unintentional release of the said sear when the said trigger is in its normal position. 55
55. In a firearm, the combination with the trigger and sear thereof; of a first locking-abutment carried by the said sear; a second locking-abutment movable by the said trigger into the path of movement of the said first locking-abutment to guard against the unintentional release of the said sear when the said trigger is in its normal position; and means movable by the said breech-bolt for retiring the said second locking-abutment. 60
60. In a firearm, the combination with the breech-bolt, trigger and sear thereof; of a first locking-abutment carried by the said sear; a second locking-abutment movable by the said trigger into the path of movement of the said first locking-abutment to guard against the unintentional release of the said sear when the said trigger is in its normal position; and means movable by the said breech-bolt for retiring the said second locking-abutment. 65
65. In a firearm, the combination with the breech-bolt, trigger and sear thereof; of a first locking-abutment carried by the said sear; a second locking-abutment movable by the said trigger into the path of movement of the said first locking-abutment to guard against the unintentional release of the said sear when the said trigger is in its normal position; and means movable by the said breech-bolt for retiring the said second locking-abutment. 70
70. In a firearm, the combination with the breech-bolt, trigger and sear thereof; of a movable transmitting-member acting when in one position to transmit the movement of the said trigger to the said sear, and movable into an inoperative position by means carried by and bodily movable with the said breech-bolt. 10
75. In a firearm, the combination with the breech-bolt, trigger and sear thereof; of a movable transmitting-member acting when in one position to transmit the movement of the said trigger to the said sear and movable into an inoperative position by means carried by the said breech-bolt; spring-means normally urging the said transmitting-member into its operative position; and retaining-means associated with the said trigger to releasably hold the said transmitting-member in its inoperative position. 15
80. In a firearm, the combination with the breech-bolt, trigger and sear thereof; of a movable transmitting-member acting when in one position to transmit the movement of the said trigger to the said sear and movable into an inoperative position by means carried by the said breech-bolt; spring-means normally urging the said transmitting-member into its operative position; and a retaining-abutment carried by the said trigger to releasably hold the said transmitting-member in its inoperative position. 20
85. In a firearm, the combination with the breech-bolt, trigger and sear thereof; of a movable transmitting-member mounted with capacity for combined rocking and bodily movement and acting when in one position to transmit the movement of the said trigger to the said sear and movable into an inoperative position by means associated with the said breech-bolt. 25
90. In a firearm, the combination with the breech-bolt, trigger and sear thereof; of a movable transmitting-member mounted with capacity for combined rocking and bodily movement and acting when in one position to transmit the movement of the said trigger to the said sear and movable into an inoperative position by means associated with the said breech-bolt. 30
95. In a firearm, the combination with the breech-bolt, trigger and sear thereof; of a movable transmitting-member mounted with capacity for combined rocking and bodily movement and acting when in one position to transmit the movement of the said trigger to the said sear and movable into an inoperative position by means associated with the said breech-bolt. 35
100. In a firearm, the combination with the breech-bolt, trigger and sear thereof; of a movable transmitting-member acting when in one position to transmit the movement of the said trigger to the said sear and movable into an inoperative position by means associated with the said breech-bolt; and spring-means seating against both the said sear and the said transmitting-member and exerting an effort to move the said transmitting-member into its operative position. 40
